CONTROL FOR ELECTRIC ELEVATORS.

1,291,561.

Specification of Letters Patent.

Patented Jan. 14, 1919.

Application filed October 2, 1914. Serial No. 384,575.

To all whom it may concern:

Be it known that I, DAVID C. LARSON, a citizen of the United States, residing in Yonkers, in the county of Westchester and State of New York, have invented a new and useful Improvement in Controls for Electric Elevators, of which the following is a specification.

My invention relates to an improved controlling system for electric elevators, and more particularly to that type of electric elevators employing direct current motive power.

One of the objects of the invention is to provide a simple and efficient electric controller for elevators arranged to eliminate so far as possible, the usage of auxiliary contacts and accompanying complications.

Another object of the invention is the provision of means employing as one of the agencies, a shunt field for effecting a dynamic brake action on the motor together with a novel method of controlling the same.

Other novel features of the invention will be pointed out hereinafter, the novel combinations of elements being set forth in the appended claims.

The accompanying drawing, represents diagrammatically a two speed electric elevator controlling system embodying my invention.

I will first designate the various parts, and thereafter point out the system of circuits showing how they act on the different parts to effect the desired results.

An elevator car C, is provided with a controlling switch S, the car being operatively connected to an electric motor M by means of the usual suspension cables. A main line or source of electrical supply is designated + and -, while P is a potential switch. The motor M is preferably compound wound, having a shunt and series field designated D and F respectively, the direction of rotation of the motor being controlled by reversing switches R, R'. An accelerating magnet is shown at H, and comprises a single magnet operating a series of contacts such as 1, 2, 3, 4, which control a starting resistance G, and series field F. A stopping magnet is shown at J, and comprises a single magnet operating a series of contacts such as 5, 6 and 7, which control a stopping resistance K. A stop motion switch is shown at L, and comprises a plurality of pairs of switches which are operated at or near the limits of car travel by means of a rod 8 and cams 9, 10 and 11. The mechanism for operating the stop motion switch is not illustrated in detail, since the same is well known in the art and is in universal use; it being sufficient to state that the rod 8 and connected cams, are rotated in one direction or the other at the limits of car travel by means of a traveling nut on the hoisting drum shaft, or in any other well known way. A brake is designated by B and is arranged to apply a friction brake to a pulley on the motor shaft by means of a weight or spring, and is released during the travel of the car by means of an electromagnet. A fast and slow speed switch is shown at E, and comprises a magnet which when energized, moves a contact 70 disk 12 out of engagement with contacts 13 and 14, controlling a resistance 15 in series with the shunt field winding of the motor. Door contacts are designated by the numeral 16, limit switch contacts by the numeral 17, and slack cable switch contacts by the numeral 18. Each of the switches P, R and R' is of the solenoid type, comprising magnet windings such as 19, 20 and 21, while the switches R and R' are also provided with the well known form of hold down coils designated 20' and 21'. A safety switch in the elevator car is designated s. The parts as shown are in their normal positions with the car at rest. Let us now assume that the operator in the car desires to go up, and that he moves the switch lever to the left into engagement with the contact segment 22. A circuit is thereby established for the windings 19 and 20 of the potential switch and reversing switch R, these windings being connected in series as follows: From + main to wire 23, car gate contacts 24 to safety switch s, wire 25 to segment 22, by way of the car switch lever, wire 26, 100 winding 20, conductor 27, to stop motion switch 28, wire 29, through the limit switches, slack cable switch and door contacts to winding 19 by way of wire 30, and thence to the - line by way of wire 31. The windings 19 and 20 now being energized, effect the operation of the potential switch and reversing switch R, thereby es-

tablishing a circuit to the motor and brake. The motor circuit may be traced from the + main, potential switch contacts 32, wire 33, reversing switch contacts 34, wires 35 and 36, hold down coil 21', wire 37, through the bottom pair of contacts 38, 38', to wire 39, contact 40, to wire 50, armature brush 51, through the armature to brush 52, wire 53, to wire 54, by way of contacts 55, resistance G, wire 56, through the series field to wire 57, and from thence through contacts 32' to the - line. The brake releasing magnet 58 is connected in parallel to the circuit just traced, being connected preferably at a point 59 substantially midway on the stopping resistance K, which is preferably a low resistance, the parallel circuit being traced as follows: from the junction 33', wire 60, through the left section of the resistance K, to junction 59, wire 61, winding 58, junction 58' and from thence to - line via wires 62 and 31. The shunt field receives current via the junction 33', wire 63, contacts 13, 14, via the disk 12, wire 64, through the field D to junction 57', and from thence to - line via wire 57 and contacts 32'. The brake being now released, the motor can start to raise the elevator, both field windings being energized. The motor will now run at slow speed, since the current flow to its armature and series field winding is limited by the starting resistance G in circuit therewith.

The accelerating magnet is connected in a well known manner in a circuit which is in parallel to the motor armature, its operation therefore depending on the C. E. M. F. of the motor. The accelerating magnet is arranged automatically to first cut out the starting resistance G in step by step order, and finally the series field winding F. In this manner the motor speed increases, and runs at its normal slow speed as a shunt machine.

It is to be here noted that the contacts 1 which are the first in order of operation by the accelerating magnet, control auxiliary contacts 1', which now closes a shunt circuit around the car switch contacts and the reversing switch operating winding, which may be traced from the + main, wire 23, contacts 24, switch s, wire 63, resistance 64, wire 65, contacts 1', wire 66, to wire 29, and from thence to the + line through the circuit including the limit and slack cable switches, the door contacts, and the potential switch winding 19. This parallel connection is productive of an important result which will be hereinafter clearly set forth.

In order to increase the speed of the motor, the operator moves the switch lever to engage the contact segment 22'. This operation establishes a circuit for the winding 67 of the fast and slow speed switch E, which may be traced from the + main, wire

23, contacts 24, to the switch lever via switch s and wire 25, segment 22', wire 68, stop motion switch 69, wire 70, winding 67 and from thence to -- line by way of wires 62 and 31. The switch E now operates to move the disk 12 out of engagement with the contacts 13, 14, thereby inserting the resistance 15 in series with the shunt field D. In this manner the shunt field is weakened, causing the motor to increase its speed, and the elevator car now travels at its normal fast speed.

In order to bring the elevator car to rest, the operator moves the car switch lever toward center position to disengage the segment 22'. This results in open circuiting the magnet 67 of the switch E, which now closes, thereby short circuiting the field resistance 15, and strengthening the field D, which causes the motor to run at a reduced speed. The continued movement of the switch lever toward center to disengage the segment 22, open-circuits the winding 20 and thus the reversing switch R opens its upper contacts 34, 55 and closes its bottom contacts 71, 72. The opening of the switch R opens the motor circuit, also the brake circuit and the circuit of the accelerating magnet H from the main line at the contacts 34 and 55, and closes a local or dynamic brake circuit around the motor by means of the lower contacts 71, 72, this circuit including the variable stopping resistance K. This local or dynamic brake circuit may be traced from the armature brush 51, which is now positive and may be considered as plus, wires 50 and 39, to wire 37 via the bottom contacts on the switch R', hold down coil 21', wires 36, 60, resistance K, wire 73 to junction 73', wire 74, hold down coil 20', and thence to brush 52, via the bottom contacts on the reversing switch R and wire 53. The motor now being driven by the load acts as a separately excited generator and sends current through the dynamic circuit, resulting in a dynamic brake or retardation on the motor tending to bring it to rest. It is to be here noted that the shunt field remains fully excited through almost the entire period of deceleration, thus exerting a field of constant strength which results in a stronger and more powerful dynamic braking action, as compared with that achieved by the introduction of any extra field winding and a resistance in series with the motor, which is now the common practice. The shunt winding as will be noted is controlled by the potential switch, which in turn is controlled by the auxiliary contacts 1' controlled by the contact 1 of the accelerating magnet. Now by reason of the construction of the accelerating magnet H, which is in accordance with that shown in the patent to J. D. Ihlder, No. 677,859, the contacts 1 and 1' will open when the motor

has decelerated to one quarter of its full speed. The opening of the latter contacts open-circuits the potential switch winding 19. The potential switch now opens its upper contacts 32, 32', and thereby open-circuits the shunt field, and closes its bottom contacts 75, 75', which contacts introduce a low resistance 76 in parallel with the circuit containing the resistance K, this resulting in a dynamic action which brings the motor down to a still slower speed. In the meanwhile a friction stop of the motor is effected by the friction brake B, which is applied gradually and easily. This gradual and easy braking action is effected by providing a path of relatively high resistance for the brake magnet discharge. The circuit forming such path includes the relatively high resistance 77 which is normally maintained in parallel circuit with the brake winding through the stop motion switches 78, 78'.

By reason of the connection of the stopping magnet J directly across the armature terminals, the same will operate its contacts to short circuit more or less of the resistance K in the dynamic brake circuit, depending upon the E. M. F. of the motor.

Referring now more particularly to the held down coils 20, 21', it will be noted that the dynamic brake current in stopping, passes through both of these coils. Now it will be observed that the reversing switches are in their open or lowermost position, and thus so long as the motor is generating any appreciable amount of current it will be impossible to close either of these switches. Furthermore it will be noted that the contacts 1', upon closing insert the resistance 64 in parallel with one or the other of the reversing switch windings 20 or 21, dependent of course on the direction of movement of the car switch. This results in weakening such winding to such an extent as to enable it to hold the reversing switch in its closed position, that is so long as the car switch maintains the circuit therefor, but such strength not being sufficient to again effect a closing of the switch (as for example by centering the car switch and quickly moving it to an operated position again) until the contacts 1' have opened. Thus there can be no possibility of again starting the motor or cause it to reverse unless and until it has substantially come to rest, or in other words, after the contacts 1, 1' are opened, which is effected upon the deceleration of the motor to approximately one quarter of its full speed. Furthermore this feature insures that the dynamic brake action on the motor in stopping, cannot be interfered with by the operator in the car, thus permitting the motor to come substantially to rest as it is intended without interference of any kind. Also when one or the other of the reversing

switches is closed to establish the motor circuit, the hold down coil of the other reversing switch tends to hold the bottom contacts thereof in firm electrical engagement, and prevents the operation of the latter switch if for any reason its winding be accidentally energized as might occur in case of an accidental short circuit or ground on the system. As a matter of fact, if it is so desired, the hold down coils may be dispensed with, and the latter explained arrangement of weakening the reversing switch windings by a parallel resistance controlled by the accelerating magnet, may be relied upon to effectively prevent sudden reversal of the motor.

If it is desired to operate the car in a descending direction, the switch lever S is moved toward the right. This movement of the lever effects the operation of the reversing switch R', and closes a circuit to the motor effecting its operation in a reverse direction to that theretofore described. The remaining parts operate in a manner as heretofore described and need no further description.

I will now point out the operation of the stop motion mechanism, it being understood that this mechanism operates only at the limits of car travel in both directions.

Assuming the car to be ascending at full speed with the car switch lever maintained in its extreme left hand position. As the car approaches its upper limit of travel, the rod 8 and connected cams 9, 10 and 11 will rotate in a left hand or anti-clockwise direction, we will say for example. By reason of the cam shapes, the switch 69 will open first, thereby interrupting the circuit to the fast and slow speed magnet switch E, and causing the latter to short circuit the resistance 15, thereby strengthening the shunt field and slowing down the motor. A further rotation of the shaft 8 effects the opening of the switch 78 which open circuits the parallel brake resistance 77, and immediately afterward the switch 28 is opened which interrupts the circuit of the operating magnet 20 of the reversing switch R, permitting the latter to open and thus disconnect the motor from its supply circuit and putting into operation the dynamic brake and friction brake, the latter being applied instantly with full power, since the discharge circuit therefor including the parallel resistance 77 is now open circuited. The potential switch in this instance is opened in a manner as heretofore described, that is, upon the opening of the accelerating contacts 1, 1'.

It is to be here pointed out that when the potential switch is opened directly as for example in a case of emergency, by means of the switch s, the ohmic resistance of the dynamic brake circuit is low, and the current generated by the motor will be of large amount, thereby effecting a maximum dy-

dynamic braking action which with the assistance of the friction brake B will rapidly bring the car to rest.

It will be further noted that since the 5 door, slack cable and limit switch contacts are placed in a series circuit with the operating windings 20, 21 and 19, protection is given against operation of the car in case any one of the above noted contacts are 10 open. Thus it will be seen that all the hatchway doors must be closed, and the limit and slack cable switches in proper condition before the car can be started.

What I claim is:

15 1. In combination, an electric motor and controlling apparatus therefor, comprising a reversing switch, a winding for operating said switch, a main line switch, a winding for operating said main line switch, the 20 winding for the reversing switch and the winding for the main line switch being in series with each other, and means to control a shunt circuit around the reversing switch winding.

25 2. In combination an elevator motor and controlling apparatus therefor, comprising a reversing switch, a main line switch, windings connected in series with each other for operating the said switches, a resistance in 30 a shunt circuit around the reversing switch winding, and contacts controlled by the motor, in the said shunt circuit.

35 3. In combination an electric motor and controlling apparatus therefor, comprising a reversing switch mechanism, a main line switch, windings connected in series for operating the said switches, a resistance in a shunt circuit around the reversing switch winding, accelerating mechanism for the 40 motor, and auxiliary contacts controlled by the accelerating mechanism to open and close the said shunt circuit.

4. The combination with an elevator car, a hoisting motor, reversing switch mechanism for the motor, a main line switch, operating windings for the said reversing and main line switches in series with each other, a switch in the car to control the series circuit, a resistance in a shunt circuit 50 around an operating winding of the reversing switch mechanism accelerating mechanism for the motor, and contacts controlled by the accelerating mechanism to maintain the said shunt circuit closed, while stopping 55 the motor.

5. In combination an electric motor, and controlling apparatus therefor comprising reversing switch mechanism for the motor, a main line switch, windings for operating the said switches, said windings being in series with each other, a manually operable switch to open and close the series circuit, a shunt circuit around both the manually operable switch and the operating windings of 60 the reversing switch mechanism, and means

operable upon starting the motor to close the shunt circuit and maintain it closed until the motor is brought substantially to rest.

6. In combination an electric motor, and controlling apparatus therefor comprising a reversing switch mechanism, a main line switch, windings for operating the said switches, said windings being in series with each other, manually operable contacts to open and close the series circuit, a resistance, 70 and means to connect said resistance in a shunt circuit around a reversing switch winding and in series with the main line switch winding.

7. In an elevator, the combination with a 75 motor, means for effecting a dynamic brake action on the motor, comprising a resistance connected in a dynamic brake circuit across the motor, an additional resistance, and electro-responsive means controlled by the 80 motor in every stopping operation for connecting the said additional resistance in parallel with the first named resistance.

8. In an elevator, the combination with a 85 motor, means for effecting a dynamic action on the motor when stopping, comprising a resistance connected in a dynamic brake circuit around the motor an additional resistance, and a potential switch controlled by the 90 motor in every stopping operation for connecting the said additional resistance in parallel with the first named resistance.

9. In an elevator, the combination with a 95 car, a motor, means for effecting a dynamic action on the motor in stopping comprising a 100 variable resistance connected in a dynamic brake circuit around the motor, an additional resistance arranged automatically to be connected in parallel with the first named resistance upon stopping the motor, and a potential switch controlled manually from the 105 car in starting, and automatically by the motor in stopping for controlling the said additional resistance.

10. In an elevator, the combination with a 110 car, a shunt wound motor, a main line circuit, means for effecting a dynamic brake action on the motor comprising the shunt field winding connected across the main line circuit, a variable resistance controlled by 115 the motor, connected in a dynamic brake circuit around the motor, an additional resistance arranged automatically to be connected in parallel with the first named resistance, means controlled automatically by the motor 120 in every stopping operation, for controlling the shunt field and said additional resistance.

11. In an elevator, the combination with a 125 motor having a field winding, a main line circuit, and means for effecting a dynamic brake action on the motor, comprising the said field winding connected across the said main line, a resistance connected in a dynamic brake circuit around the motor, and an additional resistance arranged automatically 130

- to be connected in parallel with the first named resistance, for every stopping operation of the motor.
12. In an elevator, the combination with 5 a shunt wound motor, a main line circuit, and means for effecting a dynamic braking action on the motor, comprising the shunt field connected across the main line circuit, a variable automatically controlled resistance connected in a dynamic brake circuit around the motor, and an additional resistance arranged automatically to be connected in parallel with the first named resistance at 10 every stopping operation of the motor when the speed of the motor has been substantially reduced.
13. In an electric elevator, the combination with a car, of a shunt wound motor, a main line circuit, and means for effecting 15 a dynamic braking action on the motor when stopping, comprising the shunt field connected across the main line, a resistance controlled by the varying potential of the motor, connected in a local or dynamic brake circuit around the motor, an additional resistance adapted to be connected in a parallel circuit with the first named resistance, and an electro-responsive switch controlled manually from the car in starting 20 and automatically by the motor in stopping, for controlling the shunt field and the said additional resistance.
14. In an electric elevator, the combination with a car, of a shunt wound motor, a main line circuit, means for effecting a 25 dynamic action on the motor comprising the shunt field, a variable resistance controlled by the motor connected in a dynamic brake circuit around the motor, an additional resistance, and a potential switch controlled manually from the car upon starting, and automatically by the motor upon stopping, adapted when in one position to connect the 30 shunt field across the line, and when in another position to disconnect the said field and connect the said additional resistance in parallel with the first named resistance.
15. In an electric elevator, the combination with a car, of a motor having a shunt 35 field winding, a main line circuit, a stopping resistance, a stopping magnet controlled by the motor for varying the said resistance, reversing switch mechanism arranged when open to connect the said motor and resistance in series in a dynamic brake circuit, an additional resistance, and a potential switch controlled manually from the car in starting and automatically by the motor in stopping, arranged when closed 40 to connect the shunt field across the main line, and when opened to disconnect the said field and connect the said additional resistance in a parallel circuit across the motor.
16. In an electric elevator, the combination with a car, of a motor having a shunt 45 field winding, an automatically controlled resistance, electromagnetic switch apparatus arranged to connect the said resistance in a local or dynamic brake circuit upon stopping the motor, an additional resistance, 50 and a potential switch controlled manually from the car in starting, and automatically by the motor in stopping, the switch being arranged when closed to connect the shunt field across the main line circuit, and when 55 opened to disconnect the said field and connect the said additional resistance in a parallel circuit with the first named resistance.
17. In an electric elevator, the combination with a car, a manual switch in the car, a motor having a shunt field winding, a resistance, a potential switch controlling the field and the said resistance, a reversing switch for the motor, operating windings for 60 the said switches arranged in a series circuit 55 and controlled by the car switch, a series starting resistance for the motor, means controlled by the motor for varying the said resistance, and means controlled by the resistance-varying-means for controlling a 70 parallel circuit for the potential switch winding.
18. In an elevator, the combination with a car, of a shunt wound motor, and means controlled manually from the car, and automatically by the motor for every stopping 75 operation of the motor for controlling the shunt field.
19. In an elevator, the combination with a car, of a shunt wound motor, and means 80 controlled manually from the car upon starting, and automatically by the motor for every stopping operation of the motor for controlling the shunt field.
20. In an elevator, the combination with a car, of a shunt wound motor, and an electro-responsive means controlled manually from the car upon starting and automatically by the motor for every stopping operation of the motor for controlling the shunt 85 field.
21. In an elevator, the combination with a car, a manual switch in the car, a motor having a field winding, and an electro-magnetic switch controlled by the manual switch 90 upon starting and by the motor for every stopping operation of the motor for controlling the said field winding.
22. In an elevator, the combination of a shunt wound motor, a main line circuit, and means for connecting the shunt field across the main line circuit, and for maintaining the said connection until the speed of the motor is reduced for every stopping operation of the motor substantially as described.
23. In an elevator, the combination with a car, of a manual switch in the car, a shunt wound motor, a main line circuit, and electro-responsive means controlled manually from the car upon starting and automatically 100

23. In the motor upon stopping for controlling the field winding for every stopping operation of the motor.
24. In an elevator, the combination with a car, of a manual switch in the car, a shunt wound motor, a main line circuit, an electromagnetic switch controlled by the car switch for connecting the shunt field across the line upon starting the motor, and additional means for maintaining the said connection for every stopping operation of the motor until the speed of the motor is reduced substantially as described.
25. In an elevator, the combination with a car, of a manual switch in the car, a shunt motor, a main line circuit, an electromagnetic switch controlled by the car switch for connecting the shunt field across the line upon starting the motor, and means controlled by the motor for maintaining the said connection during every period of deceleration of the motor, substantially as described.
26. In an elevator, the combination of a shunt motor, accelerating mechanism for the motor, and a potential switch controlled by the accelerating mechanism upon stopping, for controlling the field of the motor.
27. In an elevator, the combination with a car, of a shunt motor, a car switch, a main line circuit, a potential switch controlled by the car switch for connecting the field of the motor across the line upon starting, electro-responsive accelerating mechanism for the motor, and means controlled by the accelerating mechanism for maintaining the said shunt field connection until the motor speed is reduced, substantially as described.
28. In an elevator, the combination with a car, of a shunt motor, a car switch, a potential switch having an operating magnet and a circuit therefor controlled by the car switch, the said switch controlling the field winding of the motor, and means for closing an additional circuit for the potential switch operating magnet winding independent of the circuit for said winding controlled by the car switch.
29. In an elevator, the combination with a car, a car switch, of a shunt motor, a potential switch controlling the field of the said motor, and having an operating magnet and a circuit therefor controlled by the car switch, a resistance, and means controlled by the motor for establishing a circuit including the said resistance and the potential switch operating magnet winding.
30. In an elevator, the combination with a car, of a shunt wound motor, a car switch, a potential switch controlling the field of the said motor and having an operating magnet winding and a circuit therefor controlled by the car switch, electro-responsive accelerating mechanism for the motor, and an additional circuit for the operating magnet winding of the said switch controlled by the said accelerating mechanism, independently of the car switch.
31. In an elevator, the combination with a car, a car switch, a motor having a field winding, a potential switch controlling the said field, a reversing switch for the motor, operating windings for the said switches arranged in a series circuit controlled by the car switch, and means controlled by the motor for controlling a parallel circuit for the said reversing switch winding.
32. In an elevator, the combination with a car, a car switch, a motor having a shunt field winding, a potential switch controlling the shunt field circuit, a reversing switch for the motor, operating windings for the said switches arranged in a series circuit controlled by the car switch, electro-responsive accelerating mechanism for the motor, and a circuit for the winding of the potential switch parallel to said reversing switch winding and controlled by said electro-responsive accelerating mechanism for the motor.
33. In an elevator, the combination with the car, a car switch, a shunt motor, a potential switch controlling a circuit for the motor field, a reversing switch for the motor, operating magnets and circuits for the said switches controlled by the car switch, accelerating mechanism for the motor, a resistance, and a circuit for the winding of the potential switch in shunt to the reversing switch winding, said shunt circuit including the said resistance and being controlled by the said accelerating mechanism.
- In testimony whereof, I have signed my name to this specification in the presence of two subscribing witnesses.
